UNITED STATES PATENT OFFICE

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE

WARPER

Application filed January 3, 1929. Serial No. 330,096.

This invention relates to a warper for winding warp yarns drawn from a suitable supply such as a creel on to a warp beam of that type in which the warp beam rests against a driving drum and is rotated by the frictional engagement of the drum with the warp mass as the warps are wound on the beam. In this type of machine, the warp beam moves away from the driving drum as the warps are wound on the beam due to the increasing diameter of the warp mass.

The primary object of the invention is to provide a construction of this type which can be run at a high speed. The great increase in speed being demanded by the trade has rendered it difficult to control the winding operation so as to place the yarns under even tension in a homogeneous compact mass on the beam and has greatly increased the difficulty due to vibration of the warp beam when thus rotated at high speed. The present invention overcomes these difficulties and enables the desired results to be secured.

The object of the invention is further to provide means, and more particularly a cam-controlled means, for applying to the warp beam during the winding operation an additional resistance, and more particularly a frictional resistance, and for controlling the amount of additional resistance so applied to secure in correlation with the increasing total weight of the warp beam and yarn mass the desired resultant pressure of the beam on the driving drum and more particularly a gradually decreasing resultant pressure.

The invention has for its further object to provide a simple and efficient form of construction readily manufactured and readily embodied in the warper rendering it capable of high speed and producing a wound warp beam of the desired character.

These and other objects and features of the invention will appear more fully from the accompanying description and drawings and will be particularly pointed out in the claims.

Since the invention is concerned solely with the control of the warp beam during the winding operation, the preventing of the jumping or vibration of the warp beam and the provisions for doffing the warp beam, and as the

other features and mechanisms of the warper may be of any suitable construction and form, and as the general principle of operation of a warper is well known and familiar to those skilled in the art, it is only necessary here to illustrate and describe those portions of a warper directly concerned with one preferred form of embodiment of the present invention.

In the drawings: Fig. 1 is a side elevation of a warper with a simple and preferred form of the invention embodied therein and with elements of the warper not concerned with the present invention omitted.

Fig. 2 is a top plan view of the construction shown in Fig. 1.

Fig. 3 is a side elevation on a larger scale of a portion of the construction shown in Fig. 1 with the parts shown in the position reached at the end of the winding operation.

Fig. 4 is a detail chiefly in horizontal cross section taken on the line 4—4 of Fig. 3.

The warper comprises end frames such as 1 standing on the floor 2. A shaft 3 is mounted in suitable bearings 4 in the end frames and extends transversely of the warper and is driven at a high speed in any suitable manner from a suitable source of power. This shaft 3 extends through supports and rotates the driving drum 5 of the usual type.

The warp beam may be of any suitable type comprising the cylindrical barrel 6, the head 7 and gudgeons 8. The barrel of the beam rests against the driving drum and the warps 9 extend as usual from a creel or other supply through the drop wires 10 and other usual adjunctive devices over the roll 11 and are secured at their ends in any suitable manner to the barrel 6 of the warp beam. Consequently as the driving drum 5 is rotated, the frictional engagement of the drum with the beam barrel rotates the beam, winding the warp yarns thereon. The yarn mass on the warp beam therefore gradually increases in diameter until the beam is filled. Consequently also the total weight of the beam and yarn mass likewise gradually increases.

In the preferred construction, the supporting and controlling means for the warp beam

is the same at both sides of the warper so that it is sufficient to illustrate and describe the construction at one side. A supporting arm 12 is pivotally mounted on a stub shaft 13 projecting inwardly from the end frame 1 and preferably braced by a bracket 14 secured to the end frame. During the winding operation the supporting arms are held in fixed position projecting forward of the warper frame and with the upper surface 15 extending forward and upward in a convex curve of a character hereinafter described. The warp beam gudgeons during the winding operation move along the supporting surfaces 15. Preferably, as illustrated, the gudgeon 8 rotates in a gudgeon block 16 mounted to slide on the surface 15 and provided with a depending fin 17 sliding in a groove 18 formed in the upper surface of the arm 12 so as to prevent lateral movement of the gudgeon block.

The convex curved surfaces 15 of the supporting arms 12 upon which the gudgeon blocks slide are designed according to the following principle. The total weight of the warp beam, the mass of yarn thereon and, in fact, any weight or resistance to the movement of the beam away from the drum, may be resolved into two component resultant forces, one acting on a line extending through the gudgeons perpendicular to the curved surfaces 15, and the other acting on a line extending from the gudgeons to the center of the shaft 3. It is desirable that the total resultant force exerted by the warp beam on the driving drum which occurs as pressure between the beam and the drum shall not increase during the winding operation and preferably that it shall decrease from the beginning of the winding operation. With this total resultant force thus decreasing from the beginning of the winding operation, it follows that the pressure between the warp beam and the driving drum is greatest at the beginning of the winding operation. This latter result is desirable because it acts to compact the yarn in the desired manner on the beam and prevent the yarn from bulging out as it is wound on the beam so that as the winding operation proceeds, the yarn is wound under a substantially even tension in a homogeneous, properly compacted mass. In the construction illustrated and preferably employed in connection with the present invention, the curved surface 15 is so shaped that the total weight of the warp beam, the supports therefor, and the yarn mass thereon at all stages of the winding operation, considered by itself and disregarding the additional resistance herein provided to the movement of the warp beam away from the driving drum, produces a substantially constant resultant pressure against the driving drum in the direction of a line extending from the gudgeon to the center of the shaft 3. As this

total weight factor and the diameter of the warp mass are both ascertainable at each stage of the winding operation, the curve of the surface 15 is readily plotted so as to give this substantially constant pressure force on the driving drum. And as the lowermost position of the gudgeon is determined by the size of the warper, the size of the beam head, the desired clearance of the beam from the floor, etc., and as the uppermost position of the gudgeon is also limited by similar conditions, and as it is desirable that the curve of the surface 15, for convenience in manufacture, shall be a circular arc, it will be found that the curve plotted in accordance with the foregoing principles can be made readily substantially to coincide with a circular arc extending between the extreme positions of the warp beam gudgeon thus determined.

A preferred form of the present invention makes use of such a structure of warp beam support as that described by means of which the warp beam and yarn mass thereon produce a substantially constant pressure on the driving drum, although such a structure in itself considered is not novel with the present inventor. The present invention in one aspect resides in the combination with such a type of warp beam support of means for presenting an additional frictional resistance to the movement of the beam away from the drum, the effect of which frictional resistance upon the movement of the beam is automatically varied as desired and preferably so as to decrease gradually from the beginning of the winding operation so as to secure a constant gradual decrease in the pressure between the beam and the drum.

Another feature of the invention resides in the means, broadly considered, and more specifically in the form of a cam, for automatically varying and preferably for decreasing an additional resistance to the movement of the beam away from the drum irrespective of the means for supporting the beam and irrespective of the means employed for producing such resistance.

In the friction-controlled means illustrated for applying an additional resistance to the movement of the beam away from the drum, the amount of friction developed remains substantially constant throughout the given winding operation, while the mechanism through which the resistance produced by the friction mechanism is presented to the movement of the beam acts to vary as desired the resistance to the movement of the beam.

In the specific construction illustrated, which, as already noted, is the same at both sides of the warper, a bracket 19 is secured to the warper frame beneath the supporting arm and projects forwardly from the warper frame. At its forward portion this bracket is bifurcated to present the arms 20 and 21. A pair of co-operating fixed and rotary fric-

tion members are mounted in these arms. The fixed friction member is shown as a metal disc 22 having a hub 23 extending through the arm 21 and locked in place therein so as to be rigid therewith by a set screw 24. This fixed friction member is provided with a suitable friction surface such as a disc 25 of leather secured thereto by rivets 26. A sleeve 27 extends through the other arm 20 in alignment with the hub 23 and on this stud is journalled the rotary friction member shown as a metal disc 28 having a hub 29 abutting the sleeve 27. Rotary movement is imparted to the rotary friction member from a cam 30 journalled on the hub 29 and having a pawl and ratchet connection with the rotary friction member. The cam 30 is held against movement away from the friction member by means of a collar 31 secured by a set screw 32 to the hub 29. The ratchet portion of the connection between the cam and the friction member consists of ratchet teeth 33 formed on the face of the disc 28 of the rotary friction member. The pawl is shown as a pin 34 mounted to slide in the end of the cam 30 parallel with the rotary axis of the friction member. A helical spring 35 surrounds the pin 34 and is seated at one end against the shoulder formed in the cam and bears at its other end against the shouldered head of the pin thus acting to force the head toward the ratchet teeth and the head of the pin is provided with a pawl tooth 37 co-operating with the ratchet teeth 33. The pin 34 is limited in its outward movement by a retaining pin 36 extending laterally through the end thereof and having movement in a slot 36^x formed in the cam 30. The slot 36^x serves also to prevent the pin 34 from rotating.

A stud 38 extends through the sleeve 27, the hub 29 and the hub 23, thus securing them in axial alignment. At its inner end this stud is provided with a reduced threaded section 39. A washer 40 surrounds the threaded section 39 and rests against the end of the hub 23 of the fixed friction member and lock nuts 41 are mounted on the threaded section 39. At its opposite end the stud 38 is provided with a reduced section 42. A lever 43 having a bifurcated cam head 44 is pivoted at 45 on the end of this reduced portion. A helical spring 46 surrounds the reduced section 42 and extends between two washers, one 47 seated against the end of the sleeve 27 and the other 48 seated against the bifurcated cam head 44. The body of the stud 38 is of such length that it does not reach to the end of the hub 23 or the end of the sleeve 27. There is thus provided a simple and efficient means for adjusting the amount of frictional resistance to relative rotary movement of the two friction members as well as a means for quickly applying and relieving this resistance. By adjusting the lock nuts 41 on the threaded section 39, the friction members are

drawn together against the tension of the spring 46 to any desired degree. By swinging the lever 43 180° from the position shown in the drawings, the tension of the spring and consequently the frictional resistance between the two friction members is relieved. Lugs 49 projecting from the face of the arm 20 of the bracket 19 serve to position the lever 43 against rotary movement when it is in locking position.

A flexible connector shown as a chain 50 extends from the beam gudgeon 8 around, and is secured to, the cam 30. In the construction illustrated, the lower end of this connector 50 is shown as attached to a stud 51 threaded into the peripheral cam face of the cam 30 where the cam is of maximum radius. The upper end 52 of the connector 50 is secured to a cylindrical casing 53 enclosing a spring 54. An eye member 55 fits over a grooved collar 56 on the gudgeon 8 and has its stem 57 passing into the casing 53 and carrying a nut 58 threaded thereon beneath the spring. The pawl tooth 37 and the ratchet teeth 33 are so related that the cam 30 is locked to the rotary friction member when the cam 30 rotates clockwise.

The operation of this friction-controlled mechanism in presenting the required additional resistance to the movement of the warp beam away from the driving drum and in preventing jumping or vibration of the warp beam will be apparent from the foregoing description. In Fig. 1 the parts are shown at the beginning of the winding operation and in Fig. 3 at the end of the winding operation.

To place the parts in the former position, the lever 43 is rocked to release the spring 46 and the cam 30 is turned counter-clockwise and preferably so as to place the spring 54 under tension with the flexible connector 50 connected to the gudgeon 8. The nuts 41 are adjusted to give the required tension in the spring 46 and the lever 43 is placed in its locked position. The peripheral cam surface of the cam 30 is so shaped that in this position the effective leverage of the connector 50 acting to rotate the cam is on the minimum radius of the cam and in the position shown at the end of the winding operation in Fig. 3 is on a maximum radius of the cam, although this face may be shaped to give any desired result. In the construction illustrated, as the winding operation proceeds and the beam gudgeon 8 moves from the position shown in Fig. 1 to that shown in Fig. 3, the flexible connector 50 acting through the gradually varying leverage radius of the cam 30, and in this case through a gradually increasing leverage radius, rotates the cam and therewith, by reason of the pawl and ratchet connection, the rotary friction member, thus presenting the required resistance to movement of the beam. The frictional resistance between the friction members remains constant and as determined

by the tension of the spring 46, but the effect of this constant resistance upon the beam gudgeon is determined by the shape of the cam 30 and in this case is a gradually diminishing effect, so that as the total weight of the beam and yarn mass increases, the frictional resistance presented to the beam gudgeon decreases. By means of a construction such as that described, this gradually decreasing resistance may be so correlated with the gradually increasing total weight of the beam and yarn mass and the curvature of the arms supporting the beam gudgeons as to secure any desired result and in particular to secure a slight decrease in the total resultant pressure of the beam on the driving drum from the beginning of the winding operation so as to compact the yarn mass and prevent it from bulging, particularly during the earlier stages of the winding operation.

The spring 54 interposed in the connector or between the beam and the frictional resistance preferably stands in a state of distortion during the movement of the beam whether it be the normal movement along the supporting arms or an abnormal movement due to jumping or vibration, and thus acts to absorb by a change in its degree of distortion any such abnormal changes in the force exerted by the beam in opposition to the frictional resistance as would occur if the beam jumped or vibrated.

When it is desired to doff the beam, the supporting arms 12 are swung downwardly about the pivots 13 under the control of any usual and suitable mechanism and such downward movement at once acts to relieve the tension on the connectors 50 because, after the springs 54 have expanded, there is no further tendency to a pull on the connectors and the eye members 55 may then readily be lifted off from the collars on the beam gudgeons. Or, if desired, before the supporting arms are lowered, the lever 43 may be released, thus releasing the frictional resistance.

It will be noted that when the supporting arms are lowered to doff the beam, the pressure on the beam is completely relieved, the springs 54 are restored to undistorted form, the flexible connectors or chains slacken, the frictional resistance between the friction members is no longer transmitted to the beam and consequently the eye members 55 may be lifted from the beam gudgeons, leaving the beam free to be removed from the supporting arms, and it will be noted that this all takes place without any disturbance of the adjustment of the friction members. So also, with the supporting arms in their lower position, a fresh beam may readily be put in place thereon and the flexible connectors readily attached thereto, in the specific form illustrated, by again placing the eye members 55 over the beam gudgeons. Then when the supporting arms are raised, the

desired tension is automatically applied. An initial pressure may be applied, if desired, to compress the springs 54 to the desired extent by rotating the cam 30 to a new position where it will be held by the pawl 46 and ratchet 37 and 33. This also may be done without disturbing any predetermined frictional resistance of the friction members.

There is thus presented a very simple and efficient mechanism for controlling the warp beam during the winding operation in a high speed warper.

Having thus described the invention, what is claimed as new, and desired to be secured by Letters Patent, is:

1. A warper comprising a driving drum, a warp beam supported to rest against the drum and to move away from the drum as the yarn is wound on the beam by the frictional engagement of the drum therewith, means acting to cause the resultant pressure on the drum from the beam due to weight to remain substantially constant as the yarn is wound on the beam, and means for presenting a gradually decreasing additional resistance to the movement of the beam as the yarn is wound on the beam, said two means acting in conjunction to effect a gradually decreasing total resultant pressure of the beam on the drum to compact and prevent bulging of the yarn mass as the yarn is wound on the beam and to prevent the beam from jumping when rotated at high speed.

2. A warper comprising a driving drum, a warp beam supported to rest against the drum and to move away from the drum as the yarn is wound on the beam by the frictional engagement of the drum therewith, means acting to cause the resultant pressure on the drum from the beam due to weight to remain substantially constant as the yarn is wound on the beam, and means for presenting an additional resistance to the movement of the beam varying in a predetermined degree as the yarn is wound on the beam to effect a predetermined variation in the total resultant pressure of the beam on the drum.

3. A warper comprising a driving drum, a warp beam supported to rest against the drum and to move away from the drum as the yarn is wound on the beam by the frictional engagement of the drum therewith and means for presenting a gradually decreasing resistance to the movement of the beam as the yarn is wound on the beam in addition to that resulting from any weight of or carried by the beam.

4. A warper comprising a driving drum, a warp beam supported to rest against the drum and to move away from the drum as the yarn is wound on the beam by the frictional engagement of the drum therewith, means for presenting a continuous resist-

5. A warper comprising the construction defined in claim 8, in which each cam is journaled coaxially with and independently of the corresponding rotary friction member, together with a pawl and ratchet connection between each cam and said rotary friction member acting to secure the said parts together during the movement of the beam as the yarn is wound thereon.

10. A warper comprising the construction defined in claim 8, together with springs for forcing the fixed and rotary friction members into frictional engagement and means for adjusting the tension of said springs to adjust the frictional resistance between said members.

15. A warper comprising a driving drum, a warp beam supported to rest against the drum and to move away from the drum as the yarn is wound on the beam by the frictional engagement of the drum therewith, means acting to cause the resultant pressure on the drum from the beam due to weight to remain substantially constant as the yarn is wound on the beam, means for presenting an additional resistance to the movement of the beam as the yarn is wound on the beam, and a spring element interposed between the beam and said resistance and standing in a state of distortion during both the normal and any abnormal movement of the beam and acting to absorb by change in degree of distortion abnormal changes in the force exerted by the beam in opposition to said resistance.

20. 6. A warper comprising the construction defined in claim 2, together with a spring element interposed between the beam and said resistance and standing in a state of distortion during both the normal and any abnormal movement of the beam and acting to absorb by change in degree of distortion abnormal changes in the force exerted by the beam in opposition to said resistance.

25. 7. A warper comprising the construction defined in claim 4, together with a spring element interposed between the beam and said resistance and standing in a state of distortion during both the normal and any abnormal movement of the beam and acting to absorb by change in degree of distortion abnormal changes in the force exerted by the beam in opposition to said resistance.

30. 8. A warper comprising a driving drum, a warp beam having gudgeons movably supported to cause the beam to rest against the drum and to move away from the drum as the yarn is wound on the beam by frictional engagement of the drum therewith, cooperating fixed and rotary friction members at each end of the beam, a cam secured to and rotatable with each rotary friction member, and a flexible connector extending from each beam gudgeon around and secured to the corresponding cam whereby the said cams act as the beam moves during the winding of the yarn thereon to vary the leverage radius between the connectors and the rotary friction members and consequently the resistance to the movement of the beam.

35. 9. A warper comprising the construction

defined in claim 8, in which each cam is journaled coaxially with and independently of the corresponding rotary friction member, together with a pawl and ratchet connection between each cam and said rotary friction member acting to secure the said parts together during the movement of the beam as the yarn is wound thereon.

10. A warper comprising the construction defined in claim 8, together with springs for forcing the fixed and rotary friction members into frictional engagement and means for adjusting the tension of said springs to adjust the frictional resistance between said members.

15. A warper comprising a driving drum, a warp beam having gudgeons movably supported to cause the beam to rest against the drum and to move away from the drum as the yarn is wound on the beam by the frictional engagement of the drum therewith, a cam device pivotally mounted on the warper frame beneath each end of the beam, a flexible connector connected to each beam gudgeon and extending downwardly therefrom and connected to the cam device, and means for applying a constant resistance to the rotary movement of the cam devices on their pivots, the said cam devices acting gradually to decrease the amount of said resistance transmitted to the beam gudgeons during the winding operation.

20. 12. A warper comprising a driving drum, a warp beam having gudgeons, a pair of supporting arms extending forward of the drum, a pair of gudgeon blocks supporting the beam gudgeons and movable along the arms as the yarn is wound on the beam by the frictional engagement of the drum therewith, a cam device pivotally mounted on the warper frame beneath each end of the beam, a flexible connector connected to each beam gudgeon and extending downwardly therefrom and connected to the cam device, and means for applying a constant resistance to the rotary movement of the cam devices on their pivots, the said cam devices acting gradually to decrease the amount of said resistance transmitted to the beam gudgeons during the winding operation.

25. 13. A warper comprising a driving drum, a pair of supporting arms mounted for vertical movement and extending forward of the drum, a warp beam having gudgeons movably supported by the arms to cause the beam to rest against the drum and to move away from the drum as the yarn is wound on the beam by the frictional engagement of the yarn therewith, a frictional resistance means, and a flexible connector detachably connected to each beam gudgeon and extending therefrom to said frictional resistance means and acting to transmit a continuous resistance to the movement of the beam as the yarn is wound on the beam, the lowering of

the supporting arms to doff the beam acting to relieve the flexible connectors of strain and permit their ready disconnection from the beam gudgeons.

14. A warper comprising the construction defined in claim 13, together with means for adjusting the frictional resistance means to vary the resistance thereof as desired and in which the said adjustment is not disturbed by the lowering of the supporting arms to doff the beam.

15. A warper comprising the construction defined in claim 13, together with a spring element interposed in each flexible connector and standing in a state of distortion during the normal movement of the beam and in which, when the supporting arms are lowered to doff the beam, the said spring elements are restored to undistorted condition.

16. A warper comprising the construction defined in claim 13, together with a pawl and ratchet connection between each flexible connector and the said frictional resistance means to enable the connectors to be taken up when a new beam is placed in position on the supporting arms and without disturbing the frictional resistance of the frictional resistance means.

17. A warper comprising the construction defined in claim 13, together with means for adjusting the frictional resistance means to vary the amount of resistance afforded thereby, and a pawl and ratchet means between each flexible connector and said frictional resistance means to enable the flexible connectors to be taken up without disturbing the adjustments of the frictional resistance means.

18. A warper comprising the construction defined in claim 13, together with a spring interposed in each flexible connector, means for adjusting the frictional resistance means to vary the amount of resistance afforded thereby, and a pawl and ratchet means between each flexible connector and said frictional resistance means to enable the flexible connectors to be taken up and the springs to be distorted without disturbing the adjustment of the frictional resistance means.

19. In testimony whereof, I have signed my name to this specification.

HARRY A. DAVIS.
